HEAD COVERING

Joseph De Grazia, Washington, D. C.

Application October 17, 1947, Serial No. 780,558

3 Claims. (Cl. 2—205)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

This invention relates to head coverings, such as are generally referred to as hoods, and is directed to an improvement in the fit of such articles whether they form an element of a parka or are individually fabricated.

As will be readily understood this type of garment is used primarily in extremely cold climates and to reach its highest efficiency it is essential that the hood fit snugly about the head of the wearer.

It is accordingly an object of the invention to provide an oversize hood or head covering having means to automatically fit the same to the head of the wearer by contracting the same in a plurality of directions by merely drawing upon a pair of strings provided for that purpose.

It is a further object of the invention to provide a relatively large hood combined with means for more or less universally adjusting the same to the head of the wearer, to thereby greatly reduce the number of head sizes to be kept in stock.

The preferred form of the invention is illustrated in the attached drawings, in which:

Figure 1 is a perspective view of the hood as it appears in use;

Figure 2 is a rear elevational view of the disclosure of Figure 1;

Figure 3 is a rear elevational view of the hood separate from a parka and with the drawstrings in their inoperative or relaxed position;

Figure 4 is an enlarged sectional view taken on line 4—4 of Figure 3, and

Figure 5 is an enlarged detail view of a portion of the interior of the hood at a point where one of the drawstrings passes to the exterior of the hood.

As indicated above the hood of the present invention may be fabricated as a permanent part of another garment, such as a parka, or may be constructed as a separate article of wearing apparel. In this particular illustration the hood is shown as forming a part of a parka, the latter being indicated by the numeral 1 and the former by numeral 2.

The hood is fabricated in the general form of the human head by forming suitably shaped side sections 3 and connecting them with one or more central panels 4 also suitably shaped to provide the desired contour in the end product.

2

The front of the hood is provided with the usual face opening 5.

The essence of the present invention resides in the arrangement of the means for drawing the hood down to the desired size and shape to snugly fit the head of the wearer, and to this end a pair of drawstrings is arranged in the form of an inverted V or arch and is positioned on the back of the hood slightly above the neck portion.

These drawstrings are indicated by the numeral 6 and are mounted in an inverted V-shaped or arched channel formed by stitching or otherwise securing a strip of flexible material 7 on the inner surface of the hood. The inner end of each drawstring is secured at the remote end of the channel as indicated by the numeral 8, and the opposite end of the string extends to the exterior of the hood through an eyelet 9.

After the hood is placed upon the head of the wearer the drawstrings 6 are pulled, and in this action the anchored ends 8 are drawn toward each other, but due to the inverted V-shaped arrangement of the strings they serve to pull the central portion of the hood downwardly toward the base of the neck and thus contract the hood in a plurality of directions to cause the same to be brought into snug engagement with the head and effectively confine the heat generated by the body as well as excluding the entrance of cold air.

While in the present instance the drawstrings are illustrated as tied at the back of the hood after the latter has been drawn into its operative position, size and shape, they may of course be passed around the neck of the wearer and tied at the front portion of the hood if so desired.

What I claim is:

1. A head covering in the form of a hood comprising head and neck portions, said head portion provided with a face opening, said hood adapted to otherwise inclose the entire head and neck of the wearer, a channel of inverted V-shape positioned on the back of the hood with its apex located in the head portion and the lower ends of the arms of the V located in the neck portion, said hood provided with openings adjacent the lower ends of the arms of the channel, and drawstrings mounted in the channel extending through said openings and adapted to draw the hood into snug engagement with the wearer's head.

2. A head covering in the form of an oversize hood comprising head and neck portions, said head portion provided with a face opening, said hood adapted to otherwise inclose the entire head and neck of the wearer, an inverted V-shaped

channel located on the back of the hood with its apex spaced somewhat above the neck portion and with the lower ends of its arms in said neck portion, said hood provided with openings adjacent the lower ends of the arms of the channel, and drawstrings mounted in the channel extending through said openings and adapted to draw the hood into a snug fit about the wearer's head.

3. A head covering in the form of an oversize hood closed at the top and on all sides except for a face opening, a strip of material in the form of an inverted V attached to the back of the hood with the apex and arms spaced above the lower edge of the hood and providing an inverted V-shaped channel, said hood provided with openings adjacent the lower ends of the arms of the channel, and drawstrings mounted

in the channel and extending through said openings.

JOSEPH DE GRAZIA.
